GAS LIGHTER FOR A FIREPLACE, BARBECUE OR THE LIKE

Joseph T. Leighton, Tarzana, Calif.

Application November 3, 1958, Serial No. 53,253

Term of patent 14 years

(Cl. D81—25)

Fig. 1 is a perspective view of a gas lighter for a fireplace, barbecue or the like, showing my new design;

Fig. 2 is an end view of the gas lighter for a fireplace, barbecue or the like shown in Fig. 1;

Fig. 3 is an elevational view of my gas lighter for a fireplace, barbecue or the like taken from the side opposite to Fig. 1; and

Fig. 4 is a bottom view of my gas lighter for a fireplace, barbecue or the like.

I claim:

The ornamental design for a gas lighter for a fireplace, barbecue or the like, as shown.

No references cited.
